RECLINING CHAIR

Milo Baughman, Bangor, Maine, assignor to Thayer Coggin, Inc., High Point, N.C., a corporation of North Carolina

Filed July 18, 1962, Ser. No. 70,974

Term of patent 14 years

(Cl. D15—11)

FIG. 1

FIG. 3

FIG. 2

FIG. 4

FIG. 5

FIG. 6

FIG. 1 is a perspective view of a reclining chair embodying my design;

FIG. 2 is a side elevational view of the structure of FIG. 1;

FIG. 3 is a rear elevational view;

FIG. 4 is a bottom plan view;

FIG. 5 is a front elevational view;

FIG. 6 is a perspective view of the chair of FIG. 1 in its reclined position.

The dominant features of my design reside in those portions shown in full lines on the drawing.

I claim:

The ornamental design for a reclining chair, as shown and described.
